CLAIM

The ornamental design for an adjustable lighting fixture with wraparound visor, as shown and described.

DESCRIPTION

FIG. 1 is a top front perspective view of the claimed design; FIG. 2 is a bottom front perspective view of the design of FIG. 1;

FIG. 3 is a front elevation view of FIG. 1;

FIG. 4 is a back elevation view of FIG. 1;

FIG. 5 is a right side elevation view of FIG. 1;

FIG. 6 is a left side elevation view of FIG. 1;

FIG. 7 is a top plan view of FIG. 1; and,

FIG. 8 is a bottom plan view of FIG. 1.

The broken lines shown in the drawings illustrate unclaimed portions of or environmental structure related to the adjustable lighting fixture with wraparound visor, and form no part of the claimed design.

1 Claim, 8 Drawing Sheets
